UNITED STATES PATENT OFFICE

2,619,339

MINING MACHINE

Frank Cartlidge, Chicago, Ill., assignor to Goodman Manufacturing Company, Chicago, Ill., a corporation of Illinois

Application December 11, 1950, Serial No. 200,226

5 Claims. (Cl. 262—9)

1

This invention relates to improvements in coal mining machines of the kind adapted for cutting and loading coal from a mine face without an intermediate blasting operation. Various forms of such machines, designed to remove coal from the solid working face, and commonly referred to as continuous mining machines, have heretofore been proposed and employed but such machines have generally been too complicated and costly for economical operation under prevailing conditions in most coal mines.

The principal object of the present invention is to provide a machine of the general character above described which is relatively simple in construction and operation, employing as its cutting element a large cutter disc rotatable on the generally horizontal axis and mounted for horizontal swinging on the end of an elongated boom, the cutter disc also having further means for adjustment so as to be swung horizontally at different elevations in advance of the machine, and still another adjustment for positioning the cutter disc at varying angles with respect to the main boom.

A further object of the invention is to provide a gathering mechanism horizontally swingable with the main boom for collecting the cuttings as they are removed by the cutting disc, said gathering mechanism also being vertically adjustable relative to the main boom for facilitating mining operations.

The machine of the present invention has many features in common with the machine disclosed in the copending application of Frank A. Lindgren, Serial Number 193,986, filed November 3, 1950, but differs therefrom by providing greater flexibility of vertical and horizontal adjustment of the cutter disc relative to the horizontally swingable main boom and also by providing vertical tilting adjustment of the gathering mechanism with respect to the main boom.

A further object of the invention resides in the provision of an improved disc-type cutting and dislodging head having a row of peripherally disposed kerf-cutting bits adapted to undercut the face being mined and having, on its back side, inclined roller means adapted to extend into the kerf, overlapping the outstanding core, for breaking off the latter in large lumps.

Other objects and advantages of the present invention will appear from time to time as the description proceeds.

The invention may best be understood by reference to the accompanying drawings in which:

Figure 1 is a plan view of a machine constructed in accordance with my invention, showing the main boom swung at an angle toward one side of the longitudinal axis of the machine and with the cutter disc shown in full lines positioned

10

for starting a lateral cut across the end of a mine room;

Figure 2 is an enlarged detailed section of the front end of the main boom and the gathering mechanism, taken generally on line 2—2 of Figure 1;

Figure 3 is a detailed side view of the front end of the machine with parts broken away to show some of the gearing and also indicating in full and dotted lines two different permissible positions of vertical adjustment of the cutter disc with respect to the main boom;

Figure 4 is a plan view of the front end of the machine, drawn to approximately the same scale as Figure 3, with parts broken away to show certain structural details;

Figure 5 is a detailed section taken on line 5—5 of Figure 4.

Referring now to details of the embodiment of my invention illustrated in the drawings, 10 indicates generally a mobile base for the machine which, as herein shown, is supported on a pair of endless treads 11, 11 at opposite sides thereof for transporting the machine during mining operations. Since the present invention relates primarily to the swinging boom and cutting means at the front end of a mobile base, the form of base 10, shown herein for illustrative purposes, is the same as that disclosed in my copending application, Serial No. 116,684, filed September 20, 1949, so that it is necessary only to refer herein to the main structural features of said base, which are directly associated with the novel boom and cutting means of the present invention.

The base 10 carries an upright pivot pin 13 at its front end, on which is pivotally mounted a main cylindrical bearing 14 at the rear end of a horizontally swingable boom structure, indicated generally at 15. The boom structure 15, as a whole, is arranged so that it may swing laterally across the front end of the machine through angles of approximately 35° at opposite sides of the longitudinal axis of the base frame.

The base 10 has a forwardly projecting support 16 formed integrally therewith and terminating in an arcuate bearing member 17, on which a depending foot 18, forming part of the swinging boom structure 15, has slidable bearing engagement.

An articulated flight conveyor of a conventional center-chain type, indicated generally at 19, extends longitudinally of the base 10, with a forwardly and downwardly inclined front portion 30 mounted on and carried with the cylindrical bearing 14, during lateral swinging movement of the boom structure 15.

Suitable means may be provided for swinging the boom structure 15 by power. As herein shown, such means includes a hydraulic cylinder 32 fixed to one side of the base 10 rearwardly of the point of pivotal connection of the swinging

boom and said main base, said hydraulic cylinder having a cooperating piston and a piston rod 33 therein pivotally connected at its forward end to a laterally extending arm 34 formed integrally with the main cylindrical bearing 14 of the boom structure. The rear end of the hydraulic cylinder may be pivotally connected as usual (by means not shown) to the adjacent side of the base 10 to accommodate angular movement of the piston rod 33 during the swinging movement of the boom structure. Hydraulic control means for any well-known type may be provided for supplying hydraulic pressure alternately to the opposite ends of the hydraulic cylinder 32 so as to cause the boom structure to be swung horizontally by power, centered on the upright pivot pin 13. Such hydraulic control means is old and well known in the art so further details need not be shown nor described herein, as it forms no essential part of the present invention.

The boom structure, indicated generally at 15, includes a bottom plate 38 and a pair of laterally spaced upright side plates 35, 35 extending forwardly of and on opposite sides of the upright bearing 14. A pair of motor housings 36, 36 are supported as by bolts 37 on the outer sides of said plates. Said motor housings enclose electric motors for driving the cutter disc of the machine, indicated generally at 40, and also the gathering chains of the gathering mechanism, indicated generally at 41, through drive connections, as will hereinafter be more fully described.

At the forward end of each of the motor housings is a gear housing 42, also secured to the outer face of the side plates 35, 35 and forming in effect forward extensions of said plates. The front ends of the two gear housings 42 form opposed trunnion supports 43, 43 rigid with the main boom structure 15 for pivotally supporting an auxiliary boom 44 for swinging movement on a horizontal axis.

The auxiliary boom 44 consists of a hollow arm, with laterally extending cylindrical bearing members 45, 45 pivotally mounted on inwardly extending trunnions 46, 46 carried by the opposed trunnion supports 43, 43.

A relatively short arm 47 forms a supplemental extension of the auxiliary boom 44, being pivotally connected to the front end of the latter, so as to swing at right angles to the axis of swinging movement of said auxiliary boom with respect to the main boom structure 15. In the form shown herein, the pivotal connection of the supplemental arm 47 to the auxiliary boom consists of an upright pivot pin 48 passing through upper and lower extensions 49, 49 of the auxiliary boom, and also through cheeks 50, 50 projecting rearwardly from the supplemental arm, above and below the front end of the auxiliary boom, as shown in Figure 2.

The cutting disc 40 is rotatably supported on the outer end of the supplemental arm 47. As shown herein, said cutting disc is fixed as by keying on a shaft 51 having rotatable bearing longitudinally of the supplemental arm as by a plurality of anti-friction bearings 52 and 53. The drive connections for the cutter disc 40 will hereinafter be more fully described.

The auxiliary boom 44 is bodily swung by power on its horizontal trunnioned axis by a pair of hydraulic cylinders 54, 54 with cooperating pistons and piston rods 55. The rear ends of said hydraulic cylinders are pivotally connected to the upper edge of the side plates 35 of the main boom structure, and the forward ends of

the piston rods 55 are pivotally connected to upstanding arms 56, 56 on the top of the rear bearing members 45 of said auxiliary boom.

The supplemental arm 47 is moved bodily or 5 swung about its upright axis relative to the auxiliary boom 44 by a hydraulic cylinder 57 with a cooperating piston and piston rod 58. The hydraulic cylinder 57 is mounted toward the rear pivoted end of the auxiliary boom. The piston rod 58 is provided at its forward end with a rack 59 engaging a pinion 60 fixed to the upper cheek 50 of the supplemental arm 47 as by bolts 61, 61 seen in Figure 2. The rack 59 is held in engagement with its pinion 60 by a retaining strap 10 member 62, with which it is slidably engaged, the strap member being supported on its underside on the upper shoulder 63 formed on the pivot pin 48, all as shown in Figures 2 and 4.

As will be seen from Figure 3, the main boom 20 structure 15 is disposed at a substantial distance above the normal ground level as defined by the bottom level of the tractor treads 11, so as to form a generally triangular open space affording substantial vertical clearance between the axis 25 of vertical pivotal swinging movement of the auxiliary boom and the main boom structure, in all positions of said auxiliary boom.

The gathering means, indicated generally at 30 41, is supported from the main boom structure 30 within the open space below the auxiliary boom to gather loose material as it is dislodged from the working face by the cutting disc 40. Such loose material is deposited upon the front end of the downwardly inclined portion 30 of the articulated conveyor for discharge at the rear end of the machine.

The gathering means 41 shown herein consists of a double chain type gathering device of the general kind disclosed in the aforesaid application, Serial No. 116,684, which type of gathering means has heretofore been employed in loading machines, so that full details thereof need not be described herein, excepting to point out the main features thereof, consisting of a pair of endless chains 67, 67 horizontally movable about elongated guide bars 68, 68 and with gathering arms 69, 69 extending laterally therefrom and pivotally mounted to swing upwardly and downwardly with respect thereto as said gathering arms move over undulating gathering aprons 70, 70 surrounding the guide bars 68 and joined to each other by a horizontal apron 71 between said guide bars and over the front end 30 of the flight conveyor 19. The main point of distinction of 50 the gathering means in the present application over that in the above-mentioned application, Serial No. 116,684, is that the outer side portions of the aprons 70 (Fig. 3) extend as far around on each side as possible and inclined at a shallow angle with respect to the ground, in order to provide a "scooping" action in lifting material off the floor as the boom is swung from side to side. Loose material falling upon the gathering chains or upon the aprons 70 or 71 will be deposited upon 55 said front end of the flight conveyor for removal upwardly and rearwardly along the central portion of the main boom structure 15.

In the novel arrangement of gathering means disclosed herein, the entire gathering mechanism 60 is pivotally supported near its rear end for tilting movement with respect to the boom structure 15 so that the forward end of said gathering means may be bodily raised or lowered by power, to conform said gathering means to uneven mine bottoms while the machine is in op-

eration, and to facilitate the transportation of the machine from place to place in the mine with the gathering means in an elevated position. In the form shown herein, the pivotal support for the gathering means consists of a pair of forwardly and downwardly inclined, laterally-spaced brackets 72, 72 rigidly mounted on the front faces of the gear housings 42 of the main boom structure. The guide bars 68 of the gathering mechanism have housings 73, 73 beneath their rear ends, the latter housings being rigid with said guide bars and with the adjacent aprons 70 of the gathering mechanism. These gear housings are provided with outwardly extending stub shafts 74, 74 which are pivotally mounted in the lower ends of the supporting brackets 72, 72. The latter brackets thus provide a pivotal support for the gathering mechanism adjacent the rear end of the latter. Pivotal adjustment of the front end of the gathering mechanism is afforded by a pair of hydraulic cylinders 76, 76 with cooperating pistons and piston rods 77. The upper ends of the cylinders 76 are pivotally connected to the outer sides of the gear housings 42 on the main boom structure 15, and the lower ends of the piston rods 77 are each connected to an arm 78 extending rearwardly from and keyed to the outer ends of the stub shafts 74 on the gear housings 73 of the gathering mechanism. Hydraulic power is supplied from any suitable source to operate the hydraulic cylinders for controlling the raising and lowering of the front end of the gathering device as desired.

The cutting and dislodging head, generally designated 40, has a recessed front face defining an outer flanged periphery 81 and a central disc portion 79 connecting the flange with a hub 80. The hub 80 is carried on the shaft 51 as previously described. The cutting head flanged portion 81 has a plurality of cutter bits 118 adapted to cut a kerf, to define an outstanding core as will be hereinafter described. The back side of the cutting disc 40 is recessed in each of a plurality of places, as at 121, to receive an angularly disposed roller 82, the latter being rotatable about a pivot pin 83, the ends of which are respectively mounted in the peripheral flange 81 and in a corresponding boss 122. Thus, it will be observed that, when the cutting head 40 is buried in a mine face and moved across it, the peripheral bits 118 will cut a kerf to define an outstanding core between the kerf and the face. Since the roller means 82 extends into the kerf and overlaps the core, it will roll off the latter in relatively large chunks as the cutting head is swung across the room behind the face. For maximum lump size the core should be permitted to build up as greatly as possible before it is dislodged by the roller means. With this in mind it is generally best to have as few rollers as possible, consistent with the load requirements for dislodging the core formed. The back side of the disc 40 is defined by a curved surface 123 and the rollers 82 project beyond it so as to produce a wedging or "scooping" action for dislodging the overhanging coal as the cutter disc is in operation, as will hereinafter more fully appear.

Each of the motors 20, in the motor housings 36 on the main boom, has an armature pinion 85 driving a gear reduction mechanism indicated at 86 within the adjacent gear housing 42. In the form shown herein, each said gear reduction mechanism consists of gears 88, 89 and 90, the last-named gear being fixed on a longitudinally

extending shaft 92 within said housing. A gear 93 is mounted on the shaft 92 and is operably connectable to the last-named gear 90 by a clutch indicated generally at 94. This clutch may be of any suitable form well known in the art so further details thereof need not be described. The gear 93 is meshed with a gear 95 on a stub shaft 96 in the front end of the gear housing 42. A bevel pinion 97 is fixed on the front end of the last-named shaft and meshes with a bevel gear 98 on a transversely extending shaft 99 journaled concentrically in a trunnion support 43 projecting inwardly from the gear housing 42. The opposite end of the shaft 96 is journaled in the laterally extending hollow trunnion 46 at the rear of auxiliary boom 44, as by anti-friction bearing 102. A bevel pinion 103 is fixed on the inner end of the shaft 99 and is meshed with a bevel gear 104 on a shaft 105 extending centrally along the auxiliary boom 44, as shown in Figures 2 and 4.

The opposite drive motor in housing 36 has an identical train of gears affording driving connection with a transverse shaft 106 concentric with the trunnion 43 at the opposite side of the auxiliary boom 44. The two drive motors are thus designed to be driven in unison to provide power to the single longitudinally extending drive shaft 105 on the auxiliary boom 44, and having a bevel gear 107 also meshing with the gear 104 on shaft 105.

The last-named drive shaft 105 has bearing engagement near opposite ends in bearings 108 and 109, and has a bevel gear 124 engaged with bevel gear 110 loosely mounted on the pivot pin 48, which forms the axis of pivotal movement between the auxiliary boom and the supplemental arm 41, as previously described.

The bevel gear 110 is in turn meshed with a bevel pinion 111 fixed on the inner end of the shaft 51, which as previously described has the cutting disc 40 fixed on its outer end.

The gathering chains 67 of the gathering mechanism is also driven from the drive motors 20 through duplicate power transmission means shown in Figures 4 and 5. One of the gears 89 in each of the gear reduction trains 86 at opposite sides of the boom structure is meshed with a gear 87 on a stub shaft 91 and connected through universal joints 112 and in intermediate extensible shaft 113 to a worm 114 rotatably mounted in the adjacent gear casing 73 at the rear end of the gathering mechanism. The worm 114 is meshed with a worm gear 115 fixed on an upright shaft 116. A chain driving sprocket 117 is fixed to the upper end of the last-named shaft for driving the adjacent gathering chain 67 on its respective guide bar 68. Since, as previously mentioned, the two drive motors, 20, 20, are arranged to be driven in unison with each other, the two gathering chains of the gathering device will likewise be driven in unison through the duplicate transmission means just described.

The cutting disc has a plurality of cutter bits 118, 118 mounted on its flanged periphery 81, in the form shown said bits being bifurcated so as to cut a kerf substantially wider than said periphery.

The use and operation of the machine above described is as follows:

The machine may be moved into position substantially in the center of an entry or mine room as shown in Figure 1. In this figure, the working face indicated at A has been cut on a relatively wide arc by the same machine in a previous cutting operation. With the main boom structure 15 swung laterally in a clockwise direction to the

position shown in full lines in this figure, the auxiliary boom 44 is usually adjusted at a downwardly inclined angle for a cross-cut substantially as shown in Figure 3, with the lower edge of the cutter disc substantially tangential to the floor level.

To make the initial sumping cut in the mine face at the right wall or rib, the supplemental arm 47 is first swung clockwise on its axis by power into the angular position relative to the auxiliary boom 47 shown in dotted lines in Figure 1. With the main and auxiliary booms held temporarily in the same position, the supplemental arm is swung by power on its upright axis with the cutting disc in rotation, to produce a cut in the coal face along an arc of relatively short radius, until the arm 47 reaches a position substantially as shown in full lines in this figure.

Thereafter, the supplemental arm 47 is locked against further swing with the cutting disc disposed at a slightly inclined angle to the longitudinal axis of the main boom. The entire boom structure is then swung bodily about its upright axis defined by the pivot pin 13 with the cutting disc in rotation to cut a new face along an arc of relatively long radius, indicated at C in Figure 1.

As the cutter disc buries itself beneath the previous working face A, any solid core of coal remaining between said face and the new line of cut C will be broken away from the face by engagement with the snubbing rollers 82 on the inner face of the cutting disc.

To complete the cut, the main boom is swung in a counter-clockwise direction until the cutting disc reaches a desired point along the left wall or rib of the room. The cross-cut may then be completed either by withdrawing the machine bodily while the cutting disc continues to rotate or, if preferred, by swinging the supplemental arm with the cutter disc by power about its own axis, this making a cleaner tangential cut at the end of the face.

If it is desired to increase the height of the working face, the auxiliary boom 44 with the cutting disc may be raised to a higher level, as indicated in dotted lines in Figure 3, and the boom and disc, now at the left wall, may be swung to produce a second arcuate cut at a higher level.

After a completely new working face has been cut to its desired height, as above described, the machine may then be trammed forward a distance equivalent to the depth desired for the next cut of a new working face, whereupon the cutting operation above described may be repeated.

It will be understood that substantially all the coal broken down from the face will be deposited directly upon the gathering devices immediately beneath the cutting edge of the cutter disc 40 and will be carried rearwardly by the elevating conveyor 19 and transferred to the discharge conveyor for final loading into mine cars or other transporting means at the rear of the machine. Any loose coal which may drop on the floor of the mine during a cutting operation will be cleaned up when the gathering devices make their next successive swinging movement along the mine floor.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. In a mining machine, a base having mobile supporting means, a main boom supported on said base for horizontal swinging movement relative thereto, an auxiliary boom pivotally connected to said main boom for vertical swinging movement on a horizontal axis disposed forwardly of said base, an extension arm pivotally connected to said auxiliary boom for horizontal swinging movement relative thereto, and a cutting element on the outer end of said extension arm having cutter bits movable orbitally in a plane generally perpendicular to the longitudinal axes of said extension arm and auxiliary boom when the latter are extended in general alignment with each other.

2. A mining machine in accordance with claim 1, wherein drive means for the cutting element is carried on the main boom, and power transmission means extends from said drive means along said main boom, auxiliary boom and extension arm to said cutting element, operable in all positions of relative adjustment of said main boom, auxiliary boom and extension arm.

20 3. A mining machine in accordance with claim 1, wherein gathering means is supported on the main boom beneath the auxiliary boom and extension arm for sweeping engagement with the ground.

30 4. A mining machine in accordance with claim 3, wherein the gathering means includes forwardly and laterally extending aprons having laterally spaced endless chains mounted thereon, and the rear end of said gathering means is pivotally supported on a transverse axis relative to said main boom for vertical swinging adjustment of the aprons thereof relative to the ground.

35 5. In a mining machine, a mobile base, boom means supported on said base for swinging movement across a face being mined, a supplemental boom being supported on said boom means for supplemental swinging movement relative thereto, cutting means on the end of said supplemental boom comprising a disc having peripheral cutter bits and being rotatable about an axis extending longitudinally of said supplemental boom, said disc having a curved, generally frusto-conical rear end portion containing a plurality of circumferentially spaced rollers extending above the curved surface of said rear end portion and each being rotatable about an axis disposed at an acute angle with respect to the axis of rotation of the disc and extending into the kerf cut by the cutter bits when the disc is buried behind a face being mined and swung thereacross, whereby said cutter bits are effective to cut a kerf to define an outstanding core which is subsequently broken off by said rollers and dislodged rearwardly along said curved frusto-conical rear end portion.

FRANK CARTLIDGE.
